United States Patent

Des. 240,706
Patented July 27, 1976

240,706

ESCUTCHEON

James M. Palm, Jr., Rockford, Ill., assignor to Amerock Corporation, Rockford, Ill.

Filed May 13, 1974, Ser. No. 469,396

Term of patent 14 years

Int. Cl. D8—06, 09

U.S. Cl. D8—179

FIG. 2.

FIG. 3.

FIG. 4.

FIG. 5.

FIG. 1 is a front view of an escutcheon incorporating my new design.

FIG. 2 is a side view as seen from the right in FIG. 1.

FIG. 3 is a bottom view of the escutcheon.

FIG. 4 is an enlarged sectional view taken along the line 4—4 in FIG. 1.

FIG. 5 is an enlarged sectional view taken along the line 5—5 in FIG. 1.

I claim:

The ornamental design for an escutcheon, as shown.
